US0D1063557S

(12) **United States Design Patent** (10) **Patent No.:** **US D1,063,557 S**
(45) **Date of Patent:** **** Feb. 25, 2025**

(54) **INSULATED BOX**

(71) Applicant: **ThermoPod, LLC**, Dauphin Island, AL (US)

(72) Inventor: **Drayton G Miller**, Dauphin Island, AL (US)

(**) Term: **15 Years**

(21) Appl. No.: **29/828,609**

(22) Filed: **Feb. 28, 2022**

(51) **LOC (15) Cl.** 07-10

(52) **U.S. Cl.**

USPC **D7/605**

(58) **Field of Classification Search**

USPC D7/601, 602, 605, 606

(57) **CLAIM**

The ornamental design for an insulated box, as shown and described.

DESCRIPTION

FIG. 1 is a back, top, right, perspective view of an insulated box showing the claimed design;

FIG. 2 is a front, top, left, exploded, perspective view thereof;

FIG. 3 is a front, exploded view thereof;

FIG. 4 is a back, exploded view thereof;

FIG. 5 is a left, exploded view thereof;

FIG. 6 is a right, exploded view thereof;

FIG. 7 is a top view thereof;

FIG. 8 is a bottom view thereof; and,

FIG. 9 is a front, top, left, exploded, perspective view thereof, shown in a condition of use.

The dashed broken lines in the figures show portions of the insulated box and environmental subject matter that form no part of the claimed design.

1 Claim, 9 Drawing Sheets
